UNITED STATES PATENT OFFICE.

JOHN S. WILSON AND JAMES H. HASKINS, OF CHICAGO, ILLINOIS.

MACHINE FOR ROLLING THREADS ON METAL.

SPECIFICATION forming part of Letters Patent No. 295,605, dated March 25, 1884.

Application filed May 29, 1882. (No model.)

To all whom it may concern:

Be it known that we, JOHN S. WILSON and JAMES H. HASKINS, citizens of the United States, and residents of Chicago, in the county of Cook, in the State of Illinois, have invented certain new and useful Improvements in Machines for Rolling Threads on Metal, which are fully set forth in the following specification, reference being had to the accompanying drawings, in which—

Figure 1 represents a plan view of a machine embodying our improvement; Fig. 2, a vertical section of the same, taken on the line xx in Fig. 1; Fig. 3, a detail plan of the dies and die-holder; Fig. 4, a bottom plan section taken on the line yy in Fig. 2; Fig. 5, a detail plan of the timer; Fig. 6, a side elevation of the same; Fig. 7, a detail plan of the feed-wheel; Fig. 8, a detail section of the same, on an enlarged scale, taken on the line zz ; Fig. 9, a detail plan of a section of the feed-wheel on the same enlarged scale; Fig. 10, a detail elevation of a portion of the outer or stationary die on a still more enlarged scale; Fig. 11, a similar elevation of the inner or revolving die on the same scale as the last, and Fig. 12 a detail section taken on the line vv in Fig. 3 on the same scale as the last.

Our invention relates to a machine in which the threads are rolled on the metal instead of being cut, as in the ordinary lathe-machine.

We will proceed to describe in detail a machine in which we have embodied our invention in practical form, and will then point out definitely in the claims the improvements which we believe to be new and wish to protect by Letters Patent.

In the drawings, A represents a supporting-frame of any suitable construction, on which is mounted a suitable bed-piece, A', in the upper part of which is formed an inside rabbet, a , which serves as a seat for one of the threaded dies. This die B is of annular form, and is attached to a similarly-shaped block, B', by means of a tongue, b , on the die entering a corresponding groove, b' , in the block, both arranged vertically, as shown in Fig. 12 of the drawings. The block and die, fastened together, rest upon the seat in the bed-piece just mentioned, and plates C are fastened to the latter by means of screws c , extending inward over the die and block, to hold them in place.

In the outer or rim portion of the bed-piece setting-screws C are arranged at suitable intervals, which extend inward through this rim and rest upon the outer face of the die-block, so that the latter may be adjusted or sprung inward by the action of these screws. The inner or concave face of the die is provided with a series of threads, b^2 , as shown in Fig. 10 of the drawings, and there are several sections of these threads on this face of the die. This die and its block are held stationary in the machine. Within the annular die is a cylindrical die, D, fixed on a shaft, E. Its diameter is smaller than the inner diameter of the annular die, and its face is cut with a series of threads, as hereinafter more fully explained.

On the lower end of the shaft E is a bevel-gear, F, with which a corresponding pinion, G, is arranged to engage, the latter being fixed to a horizontal driving-shaft, g , mounted on the lower part of the frame, and provided with fast and loose band-pulleys $g' g^2$, which are used in the ordinary way for driving, stopping, and starting the machine; but any other suitable devices may be substituted, if desired.

On the upper end of the upright shaft a timer, H, is fastened, being arranged a little distance above the dies. This timer, as shown in the drawings, consists of a central hub, h , and radial arms h' , projecting horizontally therefrom. These arms are attached to the hub adjustably, so that they may be adjusted in a radial direction for the purpose of lengthening or shortening, as may be desired. This may be effected by a slot-and-pin connection, h^2 , as shown in the drawings, or by any other suitable device.

A feed wheel or disk, I, is mounted on a shaft, J, set in the bed-piece at one side thereof, the feed-wheel being arranged in the same horizontal plane as the timer. This feed-wheel is provided with a series of notches, i , cut into its outer edge, and adapted to receive the blanks fed thereto by any suitable mechanism, the latter not being shown in the drawings, as there are many well-known devices which are adapted to this purpose, and may readily be applied by any one familiar with this class of machines. The feed-wheel is of such size and so arranged that as it is revolved each notch will bring a blank into proper position, with its lower end in front of

the entrance to the space between the two dies, when the notch holding the blank is brought round on the inner side of the wheel, as shown in Figs. 1 and 2 of the drawings.

5 This wheel is provided with short arms or projections K, extending radially from its outer edge. It is desirable to have these projections adjustable circumferentially, for the purpose of taking up wear. We accomplish this by 10 attaching the projections to a separate piece, k, which is something like a shoe fitted to the rim of the feed-wheel. The projections and shoe may be made in one piece, the former being arranged at or near the rear ends of the latter, and at the forward ends are similar projections, k', though much shorter than the first named. The projections are provided with lugs or pins k² at their inner ends, which enter a circumferential groove, i', in the wheel. A 15 slot, k³, is cut in the shoe lengthwise, and the latter is fastened to the wheel by means of a screw, k⁴, passed through the slot and entering threaded recesses i² in the wheel. Obviously, by loosening this screw, the shoe may 20 be set back and forth on the circumference of the wheel for such adjustment as may be desired. The position of the shoe on the wheel is such that the shorter projections will be just back of the notches in the wheel.

25 The shaft J is set loosely in its bearing, being provided with a collar, j, which rests on the bed-piece, and at its lower end, underneath the latter, is surrounded by a spiral spring, j', which holds it down in place. To 30 insure the presentation of the blanks in proper position, a guide-arm, L, is attached to the bed-piece on the inside and below the feed-wheel, following the curve of the latter as it extends outward, as shown in Fig. 3 of the drawings.

35 The blanks M are delivered into the notches of the feed-wheel so as to hang by their heads, as shown in the drawings, and the relation of the timer to the feed-wheel is such that each of its arms will strike one of the longer projections on the feed-wheel as the two are 40 brought together by the revolution of the cylindrical die, the arms of the timer being so arranged thereon and adjusted that each one will move the feed-wheel forward just at the 45 proper time and just the proper distance to enter the lower end of the blank between the dies at the moment the commencement of a series of threads on the revolving die is brought to correspond or register with the series of threads commencing at the end of the 50 stationary die. The distance between the dies at the entrance where the blanks are delivered is about equal to the diameter of the blank, measuring from the edges of the threads. The 55 space between the two dies is, however, gradually constricted by springing in the stationary die under the force of the set-screws, as already explained, the adjustment being such that at the end of the path the distance between the edges of the corresponding threads 60 will be lessened to a sufficient degree to finish the rolling of the thread on the blank to the

exact depth desired. Obviously the constriction of the space between the dies will commence but a short distance from the opening, 70 so that the threads will begin to bite the blank very soon after its entrance, when it immediately begins to turn under the influence of the revolving die, and with this motion is carried along the path between the dies, the thread 75 very gradually being rolled deeper and deeper, until finally it is discharged at the other end of the path finished. The feed-wheel, under the impulse of the timer, is brought into the position shown in Fig. 1 of the drawings, so as to just 80 enter the blank between the dies, when the latter almost immediately begins to bite the blank, thereby turning it and carrying it inward, which movement carries the feed-wheel along until the blank is entered, releasing it from 85 the notch when the feed-wheel is in proper position for the next arm of the timer to take the next operative projection on the feed-wheel. The short projections back of the notches serve 90 to retain the blanks in proper position and insure their delivery to the dies.

We have shown a machine fitted for threading ordinary short bolts. If longer ones are to be operated upon, an additional wheel, N, may be mounted on the shaft J, provided with 95 ordinary notches, n, and arranged at such a distance above the regular feed-wheel as to receive the blank, and suspend it by its head in the proper position for the operation of the dies.

The machine is adapted to work on blanks 100 of different sizes by simply changing the dies, which, it will be seen by the description above, are readily removed and replaced. A corresponding adjustment of the timer and projections on the feed-wheel must, however, be 105 made to effect a proper delivery of the different-sized blanks to the dies, as will be readily understood. The construction shown in the drawings, and herein referred to, is adapted to roll the threads on half-inch bolts, in 110 which case the outer-die surface is composed of twelve sections, or blank circumference, and the inner die of ten similar sections, and the threads of the two dies differ in pitch, all as hereinafter more fully explained. It will be 115 borne in mind that the threads upon the die-faces are reversely inclined, and that as the blank is rolled between them it is rolled by the inner die over the outer, thus measuring 120 its circumference on the outer, while the inner moves upon and over it as the blank proceeds. Thus, when the blank has made one revolution from the starting-point, and is at the distance of its circumference from that point, the inner die has moved over the blank an equal distance. Further, the threads upon the dies are 125 multiple threads, that repeat the impression upon the blank as it is moved forward. The blank, in moving over the outer-die surface, commences at the starting-point of a thread, 130 and receives there an impression. In order to have this impression repeated, another thread is started on the edge of the die-face at the distance from the starting-point of the first

equal to one circumference of the blank, and so on in succession. Thus the die-face is made up of sections marked by the starting-points of threads, and is in circumference a multiple 5 of the blank circumference. The inclination of the die-threads must conform to the required pitch of the screw to be made. As the blank makes a complete revolution on each section, each die-thread must be as many of these sections in length (*i. e.*, must extend across as many sections) as the pitch of the screw requires. If, as in the example, the outer die includes twelve of these divisions, or twelve 10 times the circumference of the blank, and we 15 wish to form a screw with a pitch of one-sixth of an inch, the blank must pass over six divisions, or one-half of the whole die-circumference, and this would require a thread extending through six divisions of the die-face, 20 with an inclination of one inch from the edge or margin of the die from which the thread started. If a pitch of one-twelfth of an inch were required, in like manner it would appear that the die-thread should extend 25 through twelve divisions, or the whole die-circumference, with an inclination (or advance) of one inch. The measure therefore of the 30 length of die-face through which the die-thread will extend for an inch length of blank is the quotient arising from the division of the number of threads to the inch by the number of 35 divisions of the die. This thread obviously wrapped around the blank will go around it six times in one inch of length; but as the inner die is smaller, with the same surface movement, as we have seen, upon the blank, it must have threads of a different pitch, for the same surface movement of the smaller die upon the blank gives a greater amount of revolution to 40 that die. Therefore the die-thread must occupy a greater proportion of the die-surface, (*i. e.*, have less pitch,) and that proportion must depend upon the variation between the 45 diameters of the two dies; but the distance between the starting-points of the successive threads is the same, and the surface movement upon the blanks the same. Therefore, as a blank which is to be threaded with a pitch of one-sixth of an inch must go over a thread 50 six times its circumference in length, the same rule, as before stated, applies to laying off the threads on the inner and outer dies, which must be common multiples of the blank circumference. In the example above cited, the 55 blank being one-half inch in diameter, the inner die will be one inch less in diameter, and will have ten divisions or blank circumferences. We divide the number of threads to the inch by ten, (the number of sections,) and 60 the quotient (six-tenths) will indicate the part of the inner-die circumference which the thread will occupy, with an inclination of one inch, from the edge from which the thread started to form a screw with a pitch of six to 65 the inch.

In the construction of dies for different-sized

work similar relations are to be observed, according to the principle heretofore explained, so that the outside and inside threads will co-operate. The vertical shaft E is surrounded by a 70 bushing, O, of brass or any other suitable metal, tapering upward, the opening in the bed-piece within which the bushing is fitted being of corresponding shape. This bushing is slit down on one side, so that it may be enlarged or contracted, as occasion may require, and the latter result is accomplished by providing a thread, o, at the upper end, on which a threaded collar, P, is turned, which is seated in the bed-piece just under the circular die. 75 A collar, Q, is placed on the shaft below the bed-piece, which is also threaded, and engages with a similar thread, e, on the shaft, and is provided with a set-screw, q, by which it is fastened in any place on the shaft to which it 80 may be adjusted. The bushing is held between these two collars, and when adjustment is required by reason of wear the devices on the upper end of the shaft are removed and the upper collar turned down on 85 the bushing, thereby drawing it upward and tightening the bearing. The lower collar may also be adjusted correspondingly. These devices, as well as some other parts of the machine, may be varied without changing the 90 main characteristics of our improvement, which relates more particularly to the construction and operation of the dies by means of which the threads are rolled on the blanks. 95 We do not intend to be understood, therefore, as limiting our invention to the specific machine above described in detail; but we are aware that dies of the general form described—that is to say, an inner cylindrical and an outer surrounding die threaded to 100 form the screw—are not new, and we do not wish to be understood as claiming, broadly, 105 this combination.

We have not here shown and described mechanism for delivering the blanks to the 110 feed-wheel. Any suitable mechanism adapted to this purpose may be employed, and the mechanism for this purpose does not constitute a part of our present invention.

Having thus described our invention, what 115 we claim as new, and desire to secure by Letters Patent, is—

1. In a machine for rolling threads upon metal, an annular non-revolving threaded die, in combination with a cylindrical revolving 120 die, reversely threaded, and of less pitch than the non-revolving die, as set forth.

2. In a machine for rolling threads upon metal, an annular non-revolving threaded die, in combination with a cylindrical revolving 125 die, reversely threaded, and of less pitch than the non-revolving die, the circumference of each die being a multiple of the blank circumference adapted to the space between the die-surfaces.

3. The circular threaded die D, in combination with the curved threaded die B, pro-

vided with a tongue, *b*, the block *B'*, provided with the groove *b'*, and the set-screws *c'*, substantially as and for the purpose set forth.

4. In a machine for rolling threads upon metal, a circular revolving die, in combination with a curved non-revolving die arranged outside the former, a feed-wheel in which the blanks are held, and a timer arranged to revolve with the circular die and to act on the feed-wheel to deliver the blanks to the opening of the space between the two dies at the proper moment, substantially as described.

5. The revolving die *D*, in combination with the non-revolving die *B*, the timer *H*, mounted on the shaft of the revolving die, and provided with arms *h'*, and the feed-wheel *I*, provided with projections *K*, and mounted on

loose shaft, so as to be turned by the timer, substantially as described.

6. The feed-wheel *I*, provided with a circumferential groove, *i'*, in combination with the shoe *k*, carrying the projections *K*, and provided with pins entering the groove *i'*, substantially as described.

7. The shoe *k*, carrying projections *K*, and provided with the slot *k'*, in combination with the feed-wheel *I*, provided with the circumferential groove *i'* and the fastening-screw *k''*, substantially as and for the purposes set forth.
